UNITED STATES PATENT OFFICE.

HARRY HERTZBERG, OF BROOKLYN, NEW YORK, ASSIGNOR TO MORRIS PROPP, OF NEW YORK, N. Y.

ELECTRIC-CURRENT TAP AND CONNECTER FITTING.

Application filed June 23, 1926. Serial No. 118,000.

My invention relates to the art of electrical decorative devices and deals more particularly with a current tap and connector which are designed to permit the connection of a number of different lighting sets employing low voltage incandescent lamps arranged in series. In the decoration of Christmas trees, and the like ornamental lighting, using small incandescent lamps 10 designed to take the place of candles, groups of such lamps are connected in series across the usual house supply mains. In decorating a Christmas tree in this manner, it is necessary to have a large number of inter-connectable circuits and it is, therefore, an object of this invention to provide an improved and practical means which will permit a plurality of sets of low voltage lamps 15 to be connected together from a single source of electricity.

It is a further object of this invention to provide a comparatively inexpensive and yet efficient means for detachably joining two electric circuits.

Other objects of this invention will in part be obvious and in part hereinafter pointed out.

Certain features herein shown and described are shown, described, and claimed 30 in my co-pending application, Serial No. 117,999 filed in the United States Patent Office on the 23rd day of June, 1926, and accordingly not claimed herein.

With the above exception, the invention accordingly consists in the features of construction, combinations of elements, and arrangement of parts which will be exemplified in the construction hereinafter described, and of which the scope of application 40 will be indicated in the following claims.

In the accompanying drawing, in which is shown one of the various possible illustrative embodiments of this invention,

Fig. 1 is a plan view of a current tapping device embodying the invention applied to a Christmas tree lighting outfit, portions of the circuit being shown diagrammatically.

Fig. 2 is a side elevation view of the improved device.

Fig. 3 is a section taken on line 3-3 in Fig. 1.

Fig. 4 is a plan view showing interior side of one of the base sections of the improved device.

Fig. 5 is a plan view showing the current carrying portions and conductors removed from the base sections.

Fig. 6 is a perspective view of the current carrying portion removed from the base sections.

Fig. 7 is a plan view of a blank from which a current carrying member is formed.

Fig. 8 is a front elevational view of a modified form of the invention.

Fig. 9 is a cross-sectional view taken on lines 9-9 of Fig. 8.

Fig. 10 is a sectional view taken on line 10-10 of Fig. 9.

Fig. 11 is a perspective view of the current carrying portion removed from the modified form shown in Fig. 8.

Referring to the drawing, 10 denotes a current tap or connector embodying my invention applied to a group of low voltage 75 incandescent lamps L, such as a decorative Christmas tree lighting outfit shown diagrammatically in Fig. 1. The device 10 comprises insulated base sections 11 and 12 which are formed identically and which are 80 held together by the bolt 13. As shown in Fig. 4, the base sections 11 and 12 are formed with the grooves 14 and 15 which permit the insertion of the conductors 16, the latter being connected with a source of electricity 85 (not shown) by means of attachment plug-cap C. Current carrying members 17 which are designed to receive the plug-caps of other Christmas tree outfits or the like are formed in the following manner: Referring 90 now to Fig. 7, a blank B is made of any suitable conducting springy material to have a rectangular mid-section 18 and extension contacts 19 and 20, preferably formed at opposite edges thereof. A small flap 21 95 is stamped out of the mid-section 18 and is bent into shape to form a suitable binding terminal 17^a. The contacts 19 and 20 are then folded over the opposite faces of mid-section 18 in opposite directions that 100 is, one is folded downwardly while the other is folded upwardly so as to form said contacts into spring structures. The extension contacts 19 and 20 as well as the portions of the mid-section 18 which they overlap 105 are now bent until they are situated in planes at right angles to each other with the intermediate portions of the section 18, the binding post 17^a forming the connecting member between such bent portions. Thus, each 110

contact member 17 comprises two plates at right angles to each other and integrally united by a third plate as shown more clearly in Figure 6. Extension contacts 19 and 20 5 may be provided with protuberances or nipples 21^a which are useful in holding the blades 31 of a plug-cap 30 of a connecting circuit in the well understood manner.

Two of these members 17 which have been 10 formed as described above are now placed in suitably formed cavities 24 in the base sections 11 and 12, said members 17 being positioned with respect to each other so that if their bent faces including contacts 19 and 15 20 were extended there would be formed a square. It is also important to note here that the members 17 when mounted in the base sections 11 and 12 are placed so that the faces having the downwardly bent ex- 20 tensions are substantially parallel to each other and the faces having the upwardly bent extensions are substantially parallel to each other. It will thus be seen that the plug-cap 30 having blades 31, such as shown 25 in Fig. 2, for example, might be inserted from either side of the connector 10 and makes contact through the conductors 16 with the electrical circuit connected to the plug cap 30.

30 Referring to Fig. 8 of the drawing, I have there shown a modified form embodying my invention in the form of a connector device 110 which may be used as a means to connect two electrical circuits. I construct 35 this device exactly as described above for the current tap with the following changes:

The grooves 14 and 15 for receiving the conductors 16 are omitted from the base sections 111 and 112 for the reason that it 40 is not necessary to connect the device 110 to a source of electricity. Contact members 117 are provided which are similar in construction to the current carrying members 17 with terminals 17^a eliminated, said members 45 117 being placed in the similar base sections 111 and 112 as described above for members 17. Two plug caps 130 may now be inserted from opposite sides of the connector device 110 there being formed through the mem-

bers 117 a direct electrical contact between 50 the two plug caps.

It should be noted that the members 17 and 117 are disposed within the base sections of the connector 10 and device 110, respectively, so that the depth of said base sections 55 is substantially equivalent to the length of the blades of the connecting plug caps, although said caps may be insertable from either side of said base sections.

It will thus be seen that there is provided 60 a device in which the several objects of this invention are achieved, and which is well adapted to meet the conditions of practical use.

As various possible embodiments might 65 be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:—

75 1. A current carrying device for a current tap comprising two plates disposed at right angles to each other, a third plate integrally united with said two plates, and extensions on said first mentioned two plates folded in reverse directions.

80 2. A current carrying device for a current tap comprising two plates disposed at right angles to each other, a third plate integrally united with said two plates together, extensions on said first mentioned two plates folded in reverse directions, and a binding terminal on said third plate.

85 3. A current-carrying device for a current tap comprising two plates disposed at right angles to each other, a third plate integrally united with said two plates together, extensions on said first mentioned two plates folded in reverse directions, and a binding terminal formed from said third plate.

90 95 In testimony whereof I affix my signature.

HARRY HERTZBERG.
